UNITED STATES PATENT OFFICE.

HENRY LION, OF PARIS, FRANCE.

SOUND-PURIFYING DEVICE.

Application filed April 18, 1925, Serial No. 24,078, and in France April 23, 1924.

The apparatus for the propagation of sound which are currently employed, such as an acoustic funnel, vibrating box, vibrating conical piece and the like transmit the vibrations by the perturbations in the volume of air which they contain, but in virtue of the fact that they are likewise subject to vibration, they will prove a source of prejudicial parasitic vibrations entering into the reproduced waves.

The said parasitic vibrations may be partially attenuated by the use of devices acting against the propagation of waves in the body of the reproducing element itself. But even though it has been feasible to obviate the above-mentioned drawback, it is none the less true that the known emission devices will amplify without any diminution the parasitic vibrations due to the scraping action of the gramophone disk or the phonograph cylinder, as well as the metallic vibrations occurring in the loud speaking apparatus employed for receiving purposes in radio telephony.

My invention has for its object an apparatus for the suitable filtering of the emitted sounds, while affording the proper amplification of the normally emitted sounds, but eliminating the parasitic sounds.

This result is obtained by disposing in the path of the sound waves one or more vibrating filters consisting of series of diaphragms which are folded, embossed or corrugated, and whereof the folds, embossed parts or corrugations are angularly spaced by a suitable amount from one diaphragm to the next.

The following description relative to the appended drawings which are given by way of example, clearly explains the manner in which the invention is carried into effect.

Fig. 1 is a sectional view of an embodiment of the invention.

Fig. 2 is a corresponding perspective view, two consecutive diaphragms being shown in external view in the position which they occupy in the apparatus.

Fig. 3 is a detail view showing the superposed diaphragms on a larger scale and according to two sections at right angles.

In the form of construction shown in Figs. 1 to 3, the apparatus which is adapted for mounting upon an acoustic funnel of circular cross section consists of a drum which is made of thin wood and has formed therein the latter's slots H I, said drum be-

65
The said diaphragms *a* consist of strong paper which is folded in corrugated shape, with a depth of 5 millimeters. As shown in Figs. 1, 2, 3, the said diaphragms are superposed in such manner that the directions of the folds will be perpendicular to each other. I thus provide a vibrating arrangement of a very special form in which each diaphragm acts upon the succeeding diaphragm by the folded parts in contact, 75 whilst the vibrations of the air contained in the recesses thus formed will take place in directions which are perpendicular to each other (Fig. 3).

The whole device formed by the superposed diaphragms will offer a certain elasticity, and due to a slight pressure exercised upon the last diaphragm at G the whole device can be securely held in place.

Fig. 2 is a perspective view of the device 85 which is shown in section in Fig. 1; Fig. 3 is a full-size view showing the superposition of the diaphragms whose directions of folding are orthogonal.

The substances forming the outer envelope may be of any suitable nature such as wood, metal, plastic substance or the like, provided the said envelope is light and hardly sonorous.

As to the nature of the substances constituting the said diaphragms, the latter must be light as well as strong, and must be readily shaped for instance by folding, embossing or the like. Suitable results are afforded by glazed paper, Bristol paper and chiefly 100 by acetate of cellulose.

What I claim is:

1. A purifier of sounds, adapted to be juxtaposed or combined with an acoustic emitter, comprising a box made of light material 105 which is but little susceptible of vibration and having apertures formed in the lateral faces thereof, a plurality of corrugated diaphragms made of a light and strong substance and disposed within the said box, the 110 directions of the corrugations of each diaphragm making a certain angle with the

direction of the corrugations of the adjacent diaphragm.

2. A purifier of sounds, adapted to be juxtaposed or combined with an acoustic emitter, comprising a box made of light material which is but little susceptible of vibration and having apertures formed in the lateral faces of the box, a plurality of corrugated diaphragms made of a light and strong substance and disposed within the said box, the

directions of the corrugations of each diaphragm making a certain angle with the direction of the corrugations of the adjacent diaphragm, and means for maintaining the said diaphragms within the said box.

In testimony that I claim the foregoing as my invention, I have signed my name hereto.

15

HENRY LION.
